UNITED STATES PATENT OFFICE.

CARL BREER, OF LOS ANGELES, CALIFORNIA.

WATCH-GUARD.

No. 806,632.

Specification of Letters Patent.

Patented Dec. 5, 1905.

Application filed January 30, 1905. Serial No. 243,432.

To all whom it may concern:

Be it known that I, CARL BREER, a citizen of the United States, residing at Los Angeles, in the county of Los Angeles and State of California, have invented new and useful Improvements in Watch-Guards, of which the following is a specification.

The object of my invention is to provide a handy and reliable device to prevent the watch from accidentally slipping out of the pocket and also to prevent its being taken out surreptitiously. I accomplish these objects by means of the device described herein and shown in the accompanying drawings, in which—

15 Figure 1 is an enlarged detail elevation of my watch-guard secured to the ring of a watch in its normal position in the pocket, grasping the fabric which constitutes the front of the pocket. Fig. 2 is an enlarged side elevation 20 of my device in the position which it assumes when the watch is being removed from the pocket. Fig. 3 is a vertical section taken on line 3 3 of Fig. 1 looking in the direction indicated by the arrow. Fig. 4 is a modification thereof.

In the drawings, 1 represents a watch, and 2 the ring thereof, to which my watch-guard is attached by means of the ring 3. My watch-guard consists of the main body portion or 30 hook 4, on the return-bend of which is carried the eyelet 5, to which the watch chain or fob is removably attached. On the upper end of the guard-hook is rigidly affixed the spring 6, which extends downwardly and carries at 35 the bottom end thereof the pin 7, to which the ring 8 is secured. Pivotaly mounted on the pin 7 is mounted the fabric-engaging pawl 9. The pin 10 extends through the pawl, each end of which projects outwardly and forms the 40 upper bearing for the pawl. The shank 11 is bifurcated, as shown in Fig. 3, each member of which extends downwardly and has at the lower end thereof a return-bend 12, forming means to movably engage the projecting 45 ends of the lugs 10.

In its normal position the guard will remain as shown in Fig. 1; but when the thumb and finger are placed one on the spring 6 and the other on the portion marked 4 of the hook and 50 the thumb and finger pressed together the pawl will be thrown into the position shown in Fig. 2 and permit the removal of the watch from the pocket; but when the watch-guard

is in its normal position, as shown in Figs. 1 and 4, it cannot be removed from the pocket 55 without pressing the spring and the hook together and throwing the same into the position shown in Fig. 2, when it can be easily removed. This device will prevent the watch from falling out of the pocket and prevent 60 any one from taking it out of the pocket without the knowledge of the party carrying the watch, and it will thereby form a safe and handy attachment for placement on the watch fob or chain. The downwardly-projecting 65 free end of the hook 13 projects outwardly and adapts it to be easily passed over the fabric 14 of the pocket.

In the modified form of guard illustrated in Fig. 4 pin 7 is loose in the end of spring 6 and 70 the lugs 10 are adapted to turn merely in the lower end of the bifurcated shank 11.

I have shown and claimed my device as adapted for use on watch fobs or chains; but it may be adapted for many other uses in 75 which a handy device is required to detachably secure one object to the other and to prevent them from coming accidentally apart.

Having described my invention, what I claim as new, and desire to secure by Letters 80 Patent, is—

1. A watch-guard comprising a hook, a pawl pivotally connected to the hook, a spring attached to the upper bend of the hook and projecting downwardly parallel with the hook 85 and its free end pivoted to the pawl at a point outside of the hook.

2. A watch-guard, comprising a hook having means for attachment thereto of a watch chain or fob, a pawl pivoted to the hook, a spring attached to the upper bend of the hook and projecting downwardly parallel with the hook and its free end pivoted to the pawl, the pawl having lugs by which it is pivoted to the hook. 95

3. A watch-guard, comprising a hook having means for attachment thereto of a watch chain or fob, a pawl pivoted to the hook, a spring attached to the upper bend of the hook and projecting downwardly parallel with the hook and its free end pivoted to the pawl, the pawl having lugs by which it is pivoted to the hook, and means pivoted to an end of the pawl 100 for attachment to the ring of a watch.

4. The herein-described watch-guard comprising a hook 4, a spring 6 secured to the 105

hook at one end and provided with a bifurcated shank, a pawl pivotally connected with the hook, and bifurcated shank, said pawl having projecting lugs by which it is pivoted to the hook and a pin connected to an end of the pawl and shank, and means connected with the pin for attaching the guard to the ring of a watch.

In witness that I claim the foregoing I have hereunto subscribed my name this 23d day of 10 January, 1905.

CARL BREER.
